Primary Examiner — Deanna L Pratt*Assistant Examiner* — Lilyana Bekic(74) *Attorney, Agent, or Firm* — Law Office of Karen Dana Oster, LLC(57) **CLAIM**

I claim the ornamental design for a detachable shield for use with luggage, as shown and described.

DESCRIPTION

FIG. 1 is a first perspective view of a detachable shield for use with luggage.

FIG. 2 is a second perspective view of the detachable shield shielding the front face of luggage taken from an alternative angle.

FIG. 3 is a front view of the detachable shield.

FIG. 4 is a rear view of the detachable shield.

FIG. 5 is a first side view of the detachable shield.

FIG. 6 is a second side view of the detachable shield.

FIG. 7 is a top end view of the detachable shield;

FIG. 8 is a bottom end view of the detachable shield; and,
FIG. 9 is a plan view of the outside-presenting face of the detachable shield, the detachable shield being in the detached state.

The broken line showing of the luggage illustrates the environment of the claimed design and forms no part thereof. All other broken lines depict portions of the detachable shield which form no part of the claimed design.
